(21) Appl. No.: **29/127,518**

CLAIM

(22) Filed: **Aug. 8, 2000**

The ornamental design of a squeeze tube compressor and
creaser, as shown and described.

(51) LOC (7) Cl. **23-02**

DESCRIPTION

(52) U.S. Cl. **D6/541**

FIG. 1 is a perspective and right side elevational view of my
new design for a squeeze tube compressor and creaser; the
left side is a mirror thereof.

(58) Field of Search D6/541; 206/277;
222/95, 96, 98, 99, 101, 103

FIG. 2 is a right end elevational view thereof; the left end is
a mirror thereof;

FIG. 3 is a top plan view; and,
FIG. 4 is a bottom plan view thereof.
